UNITED STATES PATENT OFFICE.

LABRON B. ROSS, OF HAMILTON, OHIO.

METHOD AND APPARATUS FOR FORMING PAPER ARTICLES.

Application filed October 24, 1921. Serial No. 509,353.

To all whom it may concern:

Be it known that I, LABRON B. Ross, a citizen of the United States of America, and a resident of Cincinnati, in the county of 5 Hamilton and State of Ohio, have invented a new and useful Improvement in Methods and Apparatus for Forming Paper Articles, of which the following is a specification.

My invention relates to a device intended 10 for creasing blanks, such as are used for umbrellas, as disclosed in the patent to Ber- man, No. 1,325,072. My invention is con- cerned with providing means for creasing such blanks, although various forms may be 15 given to such blanks.

An object of my invention is to provide a device which will mechanically crease blanks for the purpose stated.

Another object is to provide a device for 20 the purpose stated that is simple in construction and efficient in operation.

These and other objects are attained by the means described herein and disclosed in the accompanying drawings, in which—

25 Fig. 1 is a plan view showing diagrammatically a device embodying my invention, parts being broken away.

Fig. 2 is a side elevation of the device shown in Fig. 1 showing diagrammatically 30 the relation of parts, such parts being broken away.

Fig. 3 is an enlarged fragmental view of one of the movable dies and its mounting means.

35 Fig. 4 is a sectional view on line 4—4 of Fig. 3.

My invention comprises a suitable table or bench upon which is mounted a fixed die upon which a blank may be deposited, and 40 means to mould the blank, such as a sheet of heavy paper, over the fixed die so as to crease the blank in such a way that it may be folded in the desired manner and shape.

The device A comprises a table a support- 45 ed by suitable uprights or standards a', be- tween which extend cross bars a² supporting the cam shafts a³ and a⁴ carrying suitable in- termeshing gears a⁵ and a⁶ respectively, and cams a⁷. The shaft a³ may be driven from a 50 continuously rotating shaft a⁸ and may have intermittent motion imparted to it by any suitable means such as an ordinary pulley revolvably mounted on the shaft a³, and which pulley may be driven from shaft a⁸ by 55 means of an ordinary friction clutch con-

trolled by a suitable hand lever a¹⁵. Upon the table is mounted a fixed die a⁹ which is substantially conical in form, and has formed on its upper surface tapering ridges a¹⁰, which converge upon a flat circular face a¹¹ formed at the top of the die. A blank holder a¹² is reciprocally mounted above the table and is adapted to be moved to and from a position immediately above the die a⁹. The means for actuating this blank holder comprises a frame a¹³ mounted upon the table and carrying upon its sides a¹⁴, the rollers a¹⁶, which are disposed in pairs at the forward and rear ends of each of said sides. The side bars a¹⁷ of the blank holder 70 are secured upon one another and upon the intermediate bars thereof by means of suitable cross bars a¹⁸. The side bars a¹⁷ lie between the pair of rollers a¹⁶ and have racks a¹⁹ on their lower surfaces, which racks engage with pinions a²⁰ mounted on the shaft a²¹ extending transversely of the frame a¹³. The shaft a²¹ carries at its opposite ends pulleys a²² and a²³ which normally revolve freely upon the shaft a²¹. These pulleys are 75 driven from the shaft a⁸ and are actuated in opposite directions. The clutches a²⁴ and a²⁵ are adapted to bring the pulleys a²² and a²³ into driving relation with the shaft a²¹. One of the clutch members of each of these 80 clutches, is mounted upon a bell crank lever a²⁶ and a²⁷, which levers are connected by means of cables a²⁸ and a²⁹ to suitable hand levers a³⁰ disposed at the forward end of the device, whereby either of the clutches may 85 be actuated. The lug a³¹ mounted upon the blank holder is adapted to engage the lever a²⁶ when the blank holder has reached its forward limit and to thereby disengage the pulley from the shaft a²¹ and the lug a³² is 90 adapted to engage the lever a²⁷ when the blank holder has reached its rearmost limit, and to thereby disengage the pulley a²³ from the shaft a²¹. The blank holder has mounted upon it suitable pins a³³ against which the blank may be positioned in order to center the blank over the fixed die a⁹. The bars a³⁴ and a³⁵ are mounted upon the frame a¹³ above the blank holder and support be- 95 tween them a rod a³⁶ carrying a bell crank lever a³⁷, the upper arm of which carries a weight a³⁸, and the lower end of which is pivotally connected by means of a link a³⁹ with a vertically reciprocating pin a⁴⁰ which 100 is adapted to engage the surface a¹¹ formed 105

atop the fixed die a^9 . Suitable braces a^{41} support the bars a^{34} and a^{35} . A bracket a^{42} , having its opposite ends mounted upon the bars a^{34} and a^{35} , provides a retaining means 5 for the upper end of the pin a^{40} . A slotted cross bar a^{43} extending between the forward ends of the bars a^{34} and a^{35} provides a bearing supporting the pin in a vertical position. A hand lever a^{44} pivoted at a point a^{45} upon 10 the ceiling or any other suitable place, is connected by means of a link a^{46} with the weighted arm of the vertical crank lever a^{37} , whereby the bell crank lever may be actuated about its pivotal mounting so as to 15 dispose the weight a^{38} mounted thereupon on either side of the pivotal mounting thereof upon the rod a^{36} .

The arms a^{47} are pivotally mounted at their lower ends upon the brackets a^{48} 20 mounted upon the table a . Intermediate the ends of the arms a^{47} is pivotally mounted a connecting rod a^{49} which may be varied in length by means of a turn buckle a^{50} . The lower end of the connecting rod is pivotally 25 mounted upon the one end of a lever a^{50} pivotally mounted intermediate its ends upon the bracket a^{51} and carrying a weight a^{52} at its other end. A reciprocating stem a^{53} is pivotally mounted upon the lever a^{50} and 30 carries at its free end a roller a^{54} which engages a cam a^7 . The stem a^{53} extends reciprocally through a suitable frame or bracket a^{55} mounted upon the table a . From the foregoing it is readily apparent that as 35 the shafts a^3 and a^4 are revolved, the engagement of the rollers a^{54} upon the cams causes the arm a^{47} to be moved toward or away from the fixed die a^9 . At the upper end of each of the arms a^{47} is mounted a 40 movable die a^{56} , the lower faces a^{57} and a^{58} of which are complementary to portions of the fixed die. These movable dies are suspended from the arms in the following manner.

45 A block a^{59} is pivotally mounted upon the upper end of the arm a^{47} by means of the lugs a^{60} , one each of which lie on opposite sides of an arm a^{47} . The blocks have pivotally mounted upon them at their opposite ends the links a^{61} and a^{62} , which also pivotally support the 50 movable dies a^{56} . The block carries a bracket a^{63} through which an adjustment screw a^{64} extends and which may be brought into engagement with the links a^{61} and a^{62} , and springs a^{67} which yieldingly retains the links in engagement upon the adjustment screws. The arm a^{47} carries a bracket a^{65} , between which and the movable die, extends a spring a^{66} which tends normally to retain the movable die in the position shown in Fig. 4. The springs a^{67} are mounted upon the block on the side opposite to the brackets a^{63} and engage the links on the sides opposite to those which engage the 60 screw a^{64} . The springs cooperate with the 65

aforementioned elements in retaining the parts in the relation stated.

The movable dies comprise a body a^{68} having a back a^{69} on which are mounted the lugs a^{70} , which lugs are pivotally connected 70 with the links a^{61} and a^{62} , and sides a^{57} and a^{58} which sides are complementary to the adjacent sides of adjacent ridges formed in the cone or fixed die. The movable dies are so mounted that, as the arm moves the 75 movable die toward the fixed die, the side a^{57} is first brought into engagement with the face a^{71} of ridge a^{72} and then the side a^{58} of the movable die is brought into engagement with the face a^{73} of the ridge a^{74} . The face a^{58} of the movable die is slightly narrower than the face of the ridge which it engages. The space between the end of the side a^{58} of the movable die and the top of the ridge engaged thereby, is engaged by a lug 80 a^{75} formed on the side a^{57} of the next adjacent movable die. The lug a^{75} has a face a^{76} extending from the side a^{57} at the angle as that of the apex of the several ridges in the cones and therefore, a lug a^{75} , together 85 with a side a^{58} of any movable die, will extend completely over a side a^{73} of any one ridge. From the end of the side a^{58} of each movable die, the face of the body of the die extends towards the links on such a curve 90 that the curved nose a^{77} formed on the lug a^{75} of the next adjacent movable die, can be brought into engagement with the face a^{73} of a ridge before any other part of such next adjacent movable die engages said 95 ridge. From this it is apparent that the moving dies are given a rocking or rolling motion in order to seat them between any two adjacent ridges on the fixed die. The 100 structure of one pair of the movable dies having thus been described it will be sufficient for the remaining dies, as the shafts a^3 and a^4 have similar cams a^7 spaced along their length and each movable die has a mechanism similar to that just described 105 which is actuated by one of these cams a^7 . The cams a^7 are positioned about the shafts a^3 and a^4 so as to successively operate the dies or to operate them in any sequence desired. The operation of the device is as 110 follows:

The operator actuates a lever a^{30} and causes the blank holder to be moved to a position over the fixed die. A blank of water-proofed paper is placed on the blank holder and the lever a^{44} actuated so as to move the pin a^{40} to the position shown in Fig. 2, the pin serving to retain the blank on the cone as the blank holder is moved from over the fixed die when the operator actuates the other hand lever a^{30} . The hand lever a^{15} is then actuated and the cams a^7 revolved. The cams bear such relation that the arms a^{47} are successively brought toward the paper 120 blank. As the first arm approaches the 125

- fixed die, the nose on the movable die carried thereby engages the paper blank, and as the movable die moves about the pivots mounting it and the links upon one another 5 and upon the block, the face on the lug is brought into engagement with the blank. The further movement of the arm brings the side a^{57} of the movable die into engagement with the face a^{71} of the first ridge on 10 the cone. After the whole of the side a^{57} engages the blank, the further movement of the arm brings the side a^{58} of the movable die into engagement with the adjacent face of the adjacent ridge and the further movement 15 of the arm causes the movable die to crease the paper at the bottom of the ridges. The lugs a^{75} crease the blank over the apex of the several ridges. It should be observed that blanks for the purpose stated are generally 20 provided with a flat panel and in order to accomplish this, the first lug may be provided with a nose having a curved underside as disclosed in Fig. 4. After one movable die has been seated upon the blank, 25 the next movable die is brought into operation by the cams. When all the movable dies have been seated upon the blank, they are then lifted from the blank, which will then have been creased in the desired manner. The creased blank is then folded 30 and is passed through a pair of parallel rollers such as a wash ringer in order to augment the lines of crease if not sufficiently pronounced.
- 35 What I claim is:
1. A method for creasing waterproofed paper comprising successively moulding portions of the blank over a fixed die and of retaining the moulded portion upon the fixed die while moulding succeeding portions of the blank.
  2. A method of creasing flexible foldable material of the kind described, consisting of securing the material at a given point, 45 and of successively creasing sectors of the material on lines radiating from the secured point.
  3. A method of creasing flexible foldable material of the class described, comprising 50 securing the material at a determinable point upon a fixed die, and of successively bringing movable dies into engagement with portions of the material so as to crease the material, and of retaining each succeeding 55 movable die in engagement upon the material until all the movable dies have performed their work upon the material.
  4. An apparatus for creasing waterproofed, 60 flexible, foldable material, comprising a fixed die, means to secure a blank of said material upon the fixed die, and means to successively mould adjacent portions of the blank over the fixed die.
  5. An apparatus for creasing waterproofed, 65 flexible, foldable material, comprising a
- fixed die, movable dies mounted radially in relation to the fixed die and each movable die being adapted to mold a sector of the material, means to secure the material at a point central to the radii upon which the movable dies are mounted, and means to actuate the movable dies.
6. An apparatus for creasing waterproofed, 70 flexible, foldable material, comprising a fixed die, movable dies mounted radially in relation to the fixed die and each movable die being adapted to mold a sector of the material, means to secure the material at a point central to the radii upon which the movable dies are mounted, and means to actuate the movable dies.
7. An apparatus for creasing waterproofed, 75 flexible, foldable material, comprising a table, a fixed die mounted upon the table, movable dies mounted pivotally on the table, means adapted to secure a blank of said material on the fixed die, and means to successively bring the movable dies into engagement with the fixed die.
8. In a device of the class described, the combination of a fixed die, a blank holder adapted to be reciprocated to and from a position above the fixed die and to position a blank above the die, means adapted to secure the blank upon the fixed die, and movable dies adapted to successively mould radially extending segments of the blank on the fixed die.
9. In a device of the class described, the combination of a table, a fixed die mounted on the table, a blank holder reciprocally mounted upon the table, means to move the blank holder to and from a position above the fixed die, movable dies pivotally mounted upon the table, means to secure a blank upon the fixed die, and means adapted to successively actuate the movable dies and to bring them into engagement with the fixed die in the sequence of their mounting upon the table.
10. In a device of the class described, the combination of a table, a fixed die mounted on the table, movable dies mounted on the table, means to secure a blank upon the fixed die, a cam shaft mounted on the table, cams mounted on the cam shaft, and a connection between the cams and the movable dies, the cams being adapted to successively actuate the movable dies in the order of their mounting.
11. In a device of the class described, the combination of a table, a fixed die mounted on the table, movable dies mounted on the table, a blank holder mounted on the table, means to move the blank holder to and from a position above the fixed die, means to secure a blank upon the fixed die, a cam shaft mounted on the table, cams mounted on the cam shaft, and connections between the

cams and the movable dies, the cams being adapted to successively bring adjacent movable dies into engagement with the fixed die.

5 12. In a device of the class described, the combination of a table, a fixed die mounted on the table, movable dies mounted on the table, a blank holder mounted on the table, means to move the blank holder to and from 10 a position above the fixed die, means to secure a blank upon the fixed die, a cam shaft mounted on the table, cams mounted on the cam shaft, and connections between the cams and the movable dies, the cams being adapted 15 to successively bring adjacent movable dies into engagement with the fixed die, and to retain the movable dies in engagement with the blank until all of the movable dies have performed their work upon 20 the blank.

13. In a device of the class described, the combination of a conical fixed die having ridges radiating from the apex thereof, movable dies mounted adjacent to the fixed die 25 and each being adapted to seat in one of the grooves between adjacent ridges and to extend over the top of one of said ridges, and means to give to the movable dies a rolling motion as they are moved into engagement with the fixed die whereby the movable die will be brought into engagement with the face of one ridge of the fixed die before being brought into engagement with any portion of the succeeding adjacent 30 faces of the ridges.

14. In a device of the class described, the combination of a fixed die having a conical shape and ridges radiating from the apex thereof, arms mounted pivotally adjacent 40 the fixed die, blocks pivotally mounted upon the arms, movable dies adapted to seat in the grooves between adjacent ridges on the fixed die, links having their opposite ends pivotally mounted upon the movable dies 45 and blocks, brackets mounted on the blocks, and means yieldingly retaining the movable die in such position that the links are held in engagement with the brackets, and means to actuate the arms.

50 15. In a device of the class described, the combination of a fixed die having a conical shape and ridges radiating from the apex thereof, arms mounted pivotally adjacent the fixed die, blocks pivotally mounted upon 55 the arms, movable dies adapted to seat in the grooves between adjacent ridges on the fixed die, links having their opposite ends pivotally mounted upon the movable dies and blocks, brackets mounted on the blocks, 60 means yieldingly retaining the die in such position that the links are held in engagement with the brackets, and means to successively actuate the arms whereby adjacent movable dies are successively brought into 65 engagement with the fixed die.

16. In a device of the class described, the combination of a conical fixed die having ridges radiating from the apex thereof, movable dies each having a moulding face complementary to those portions of succeeding 70 ridges extending from the place adjacent the apex of one ridge to the opposite face of said ridge and a portion of the face of the adjacent ridge, and means to actuate the movable dies in such manner that the first mentioned portion of the movable die will be brought into engagement with the first mentioned face of a ridge on the fixed die, and which contact between the movable and fixed dies then becomes a pivot about which the 75 remainder of the movable die is actuated as it is moved toward its seat between the said ridge and the next adjacent ridge.

17. In a device of the class described, the combination of a conical fixed die having 80 ridges radiating from the apex thereof, movable dies each having a moulding face complementary to those portions of succeeding ridges extending from the place adjacent the apex of one ridge to the opposite face of said ridge and a portion of the face of the adjacent ridge, means to actuate the movable dies in such manner that the first mentioned portion of the movable die will be brought 85 into engagement with the first mentioned face of a ridge on the fixed die, and which contact between the movable and fixed die then becomes a pivot about which the remainder of the movable die is actuated as it is moved toward its seat between the said ridge and the next adjacent ridge, and means 90 to successively actuate the movable die in the order of the ridges which they engage.

18. In a device of the class described, the combination of a fixed die, arms mounted 105 pivotally adjacent the fixed die, a block mounted pivotally upon each arm, movable dies, links pivotally connecting the movable dies and the blocks, brackets mounted on the arms, brackets mounted upon the blocks, adjustment screws mounted upon the second mentioned brackets, and means mounted upon the first mentioned brackets and upon the movable dies yieldingly retaining the links in engagement with the set 110 screws.

19. In a device of the class described, the combination of a fixed die, arms mounted pivotally adjacent the fixed die, a block mounted pivotally upon each arm, movable dies, links pivotally connecting the movable dies and the blocks, brackets mounted on the arms, brackets mounted upon the blocks, adjustment screws mounted upon the second mentioned brackets, means mounted upon the first mentioned brackets and upon the movable dies yieldingly retaining the links in engagement with the set screws, and means mounted on the block yieldingly bearing 115 upon the links and yieldingly cooperat- 120

ing with the yieldable means mounted on the first brackets in maintaining the links in engagement upon the said screws.

20. In a device of the class described, the combination of a table, a fixed die mounted on the table, a blank holder adapted to be moved to and from a position above the fixed die, means adapted to actuate the blank holder moving means, means to automatically render the blank holder moving means

inoperative upon the blank holder, means to secure a blank upon the fixed die, movable dies adapted to be brought into engagement with the fixed die, means adapted to actuate the movable dies, and means to control the movable die actuating means.

In testimony whereof, I have hereunto subscribed my name this 21st day of October, 1921.

LABRON B. ROSS.
